UNITED STATES PATENT OFFICE.

BENOIT JOSEPH XAVIER GOSELIN, OF LONDON, ENGLAND.

BOTTLE AND LIKE VESSEL.

1,273,479.

Specification of Letters Patent.

Patented July 23, 1918.

Application filed September 28, 1917. Serial No. 193,682.

To all whom it may concern:

Be it known that I, BENOIT JOSEPH XAVIER GOSELIN, a subject of the King of England, residing at London, England, have 5 invented certain new and useful Improvements in Bottles and Like Vessels, of which the following is a specification.

This invention relates to improvements in bottles or like vessels for liquids, and has for 10 its object to provide means whereby the liquid, for example ink, contained in the bottle, may be brought to a convenient level for use when the general level in the bottle is lower than is convenient for use.

15 According to the present invention a vessel for containing liquid comprises the combination of a main container for the liquid having a single opening, a dipping well within the container arranged under the 20 opening, and a rigid-walled filling chamber for the dipping well above the open mouth thereof to hold liquid when the vessel is inverted communicating both with the container and with the mouth of the dipping 25 well.

The term "dipping-well" as used throughout this specification and claims will be understood to include a like well whether used for dipping, as for example when applied to an inkpot into which a pen is dipped or for other purposes, as for example holding water for the use of birds.

The invention will be described as applied to an ink-bottle, though, as stated above, it 35 is not restricted to this application. In the accompanying drawings—

Figure 1 is a vertical section through an ink-bottle constructed according to one method of carrying out this invention, and 40 Figs. 2 to 5 are vertical sections each through a different construction of ink-bottle according to the present invention.

The same letters indicate the same parts throughout the drawings.

45 The bottle shown in Fig. 1 is in the form of a main container B divided by a diaphragm B¹ into a lower portion and an upper chamber S, herein referred to as a filling chamber. Openings O in the diaphragm 50 afford communication between the chamber S and the space beneath it.

Depending from the diaphragm is a tube-like dipping well R whose upturned open mouth opens into the filling chamber S. 55 Immediately above the mouth of the dipping

well is a neck in the top wall of the container, provided with a cork or stopper E.

The use of this bottle is as follows:—

The level of the ink in the container may be only that indicated by the line C, but by 60 inserting the cork E, tipping the bottle up so that ink flows through the openings O and collects in the chamber S, and then turning the bottle back to its normal position, the ink will fill the well R approximately to 65 the level indicated by the line D. The cork E can then be removed and the well R supplies the ink required for immediate use. When the ink has got too low in the well R, the well must be replenished by again tip- 70 ping up the bottle as already described.

In Fig. 2 the "dipping-well" is carried from the bottom of the container and has an enlargement R¹ at the top which cooperates with the top of the bottle to provide the 75 equivalent of the chamber S of Fig. 1. The well is filled by inverting the bottle so that the liquid flows around between the enlargement and the sides of the container and thus enters the "dipping-well" when the vessel is 80 re-inverted.

In Fig. 3 a detachable "dipping-well" is again provided, being carried in a plug J which is pushed into an opening at an angle to the vertical. The plug J has a hollow 85 enlargement S¹ outside the container and beyond this enlargement is provided with a neck to take the stopper E. The enlargement S¹ enables a considerable body of ink to collect in it when the container is tipped 90 up so that the well R is filled.

In Fig. 4 the well is attached to the container in a manner similar to that shown in Figs. 1 and 2, but instead of the solid stopper E, a hollow stopper S² is secured in the 95 neck of the bottle. This stopper S² serves the same purpose as the enlargement S¹ and the plug J in Fig. 3, but the stopper is removed when the "dipping-well" is to be used.

100 In Fig. 5 the "dipping-well" R is removable and rests by means of a flange T on a shoulder S³ formed by a constricted portion of the container B. When this bottle is tipped up the well R moves sufficiently to 105 allow the ink to pass the constricted portion of the container and then when the vessel is re-inverted sufficient ink will flow into the well R for use. The flange T may be fluted if desired to prevent it from stopping the 110

2
back flow of the ink if more should flow into the top of the container than can be received by the well R.

Although a considerable number of modifications of this invention have been described in this specification, it will be appreciated that further modifications can still be made without departing from the spirit of this invention.

10 What I claim as my invention and desire to secure by Letters Patent is:—

1. A vessel for containing liquid comprising the combination of a main container for the liquid having a single opening, a dipping well within the container arranged under the opening, and a rigid-walled filling chamber for the dipping well above the open mouth thereof to hold liquid when the vessel is inverted, communicating both with the container and with the mouth of the dipping well.

15 2. A vessel for containing liquid, comprising the combination of a main container for

the liquid having a single opening, a dipping well within the container arranged 25 under the opening, a hollow plug for the said opening constituting a rigid-walled filling chamber for the dipping well above the open mouth thereof to hold liquid when the vessel is inverted, and communicating both 30 with the container and with the mouth of the dipping well.

3. A vessel for containing liquid, comprising the combination of a main container for the liquid having a single opening, a hollow 35 removable plug arranged in the opening in the container, and constituting a dipping well within the container, said plug having a rigid-walled filling chamber above the open mouth of the dipping well to hold liquid 40 when the vessel is inverted, and a passage through the wall of the plug communicating with the container.

In testimony whereof I affix my signature.

BENOIT JOSEPH XAVIER GOSSELIN.
